UNITED STATES PATENT OFFICE

2,244,737

LIGHTING FIXTURE

Lemuel L. Stewart, Elkhart, Ind., assignor to The
Adlake Company, a corporation of Illinois

Application December 31, 1937, Serial No. 182,859

2 Claims. (Cl. 240—7.35)

Due to limitations in available power, lighting fixtures used on railway cars, buses and the like, should provide sufficient illumination at the reading plane for easy reading, but no more general illumination than is required for practical purposes. Highly efficient, specially designed lighting fixtures are necessary to meet specifications of this kind, and the principal object of this invention is to provide such fixtures.

A further object of the invention is to introduce color into the light which is given off by the fixture without materially impairing the efficiency of the fixture as a whole.

Practicability of fabrication, ease of maintenance, and cheapness in cost are other desirable attributes of the fixtures shown in the accompanying drawings, in which

Fig. 1 is a fragmentary cross-sectional view of a railway car equipped with lighting fixtures made in accordance with this invention;

Fig. 2 is a cross sectional view showing one of the preferred forms of the invention;

Fig. 3 is a bottom plan view of the fixture shown in Fig. 2;

Fig. 4 is a fragmentary cross-sectional view showing fixtures built into the underside of the baggage racks;

Fig. 5 is a cross sectional view through the fixture shown in Fig. 4;

Fig. 6 is a bottom plan view of the fixture cover shown in Fig. 5, a portion being cut away, as indicated by the section line 6—6 in Fig. 5;

Figs. 7 and 8 show modified forms;

Fig. 9 is a cross sectional view of a railway car which, for the purposes of illustration, is equipped on the left side with the fixture shown in Figs. 10 and 12, and on the right side with the fixture shown in Figs. 11 and 13;

Figs. 10 and 11 are bottom plan views of the fixtures shown in Figs. 12 and 13, respectively; and

Figs. 12 and 13 are sectional views showing another type of fixture coming within the broad scope of this invention.

The choice of certain preferred and modified forms of the invention for illustration and description is for the purpose of complying with sec. 4888 of the Revised Statutes, but it should be understood that the claims should not be limited by these specific embodiments of the invention unless required by the prior art.

In designing the electrical equipment for a railway car, the engineer in charge usually allows a given number of watts, say 1500 watts, for the car lighting equipment. Other electrical

power demands are similarly budgeted and then the size and electrical characteristics of the generator, relays and other electrical equipment are determined.

5 The recent trend toward light-weight cars necessitates cutting down on the weight of the electrical equipment carried by each car, with the result that every effort is being made at the present time to reduce the amount of power required for car lighting. To accomplish this end, highly efficient lighting fixtures must be used.

Broadly speaking, the problem can best be handled by using efficient spotlight units which give the required illumination at the reading plane, but no more general illumination than is necessary for lighting the aisles and giving a general pleasing effect to the car interior.

The fixtures shown in the drawings and hereafter described accomplish these objects and meet the other requirements of practical design by having a minimum number of parts, by being easy to maintain, and by being capable of adjustments which enable the desired lighting characteristics to be readily obtained after the installation of the fixtures has been completed.

Referring now to Figs. 1-3 inclusive, lighting fixtures generally designated 20, are shown mounted on the ceiling of the lower deck of a railway car 21, one fixture being mounted above each pair of seats 22. The fixtures are recessed into the lower deck ceiling, the finish sheet of which is indicated at 23 (Fig. 2) and each comprises a standard lamp 24 screwed into a socket 25 which is adjustably supported by a collar 26 which rests upon and is capable of lateral adjustment relative to a reflector generally designated 27.

The reflector is shown as a sheet metal stamping having a polished reflecting surface 28, but it may be of any approved design and preferably is provided with a screw thread 29 adjacent to its mouth to receive the threads 30 formed on the glass cover, which is generally designated 31. The threads 29 of the reflector may terminate in a marginal flange 32.

The collar 26 is split, as indicated at 33, to provide a clamping jaw 34 which may be made to grip the socket 25 and hold it in any desired adjusted position along a vertical axis by the tightening of a screw 35. Lateral adjustment of the lamp within the reflector 27 is accomplished by movement of the collar 26 on the top flat surface 36 of the reflector, the desired adjusted position being held by a small screw 37 which travels in a slot 38 provided in the collar 26.

The fixture is preferably ventilated by providing openings 39 and 40 in the reflector, or it may be made of a suitable heat dissipating material such as aluminum.

The fixture cover 31 is made of glass or other suitable transparent material as for example certain plastic material of which

Phenol-formaldehyde compounds,
Urea-formaldehyde compound,
Methyl-methacrylate resin,
Cellulose acetate

are the most suitable. The cover comprises a lens portion 41 and light diffusing portion 42, the former having its radius of curvature chosen to give the desired distribution of concentrated light on the reading plane immediately beneath the fixture. The light diffusing portion 42 of the cover preferably has a plurality of annular prisms or ribs 43 which are shaped to provide evenly distributed illumination or any other desired distribution of light.

The cover 31 is readily secured to the fixture by screwing it into the reflector 27, the upper margin of the cover being serrated as indicated at 44 to cooperate with a spring pawl 45 which locks the cover in place and prevents it from accidentally being unscrewed by jarring of the car.

It will be observed that the light from the lamp 24 is concentrated by the reflector 27 on the lens portion 41 of the cover and the lens serves to collect the light rays and transmit them in the form of a beam on the reading plane below. A certain amount of light, however, will pass out laterally through the diffusing portion 42 of the cover and the prisms 43 will serve to distribute these rays according to general illumination requirements. The prisms bend the light rays from the source laterally and upwardly to provide general illumination for the upper portion of the car without glare to the passengers below.

It is possible to give the vertical beam emanating from the fixture a quality of color (the lamp 24 being a source of white light) by placing a color screen 46 along the inner wall of the light diffusing portion 42 of the cover. The screen may constitute a relatively thin sheet of gelatin or other colored translucent or transparent material, or it may consist of colored enamel sprayed on the inner wall by well known methods. Some of the light rays which would normally pass through the light diffusing portion of the cover will be deflected by the screen through the lens 41 and when the color screen is blue, for example, the vertical beam will have a certain daylight quality which improves it for reading purposes.

Of course the rays passing through the light diffusing portion 42 of the cover will also be colored, and the color in the region will be more pronounced because only those rays which correspond in wave length to the transmission band or bands of the color screen will go through the screen.

It should be noted that the efficiency of the vertical beam is not impaired in the least by the addition of color since the screen is not placed in the path of the main beam, but only intercepts certain laterally directed rays which otherwise would pass through the diffusing portion 42 or be reflected as white light by the inner surface of that portion.

In Figs. 4-6 inclusive, a somewhat similar fixture is shown mounted in the baggage racks extending longitudinally of the car. The cover in this instance may have a smooth rounded outer surface to make it simulate a crystal ball, but as before, the cover 31 has a lens portion 41 and a light diffusing portion 42. The glass in the diffusing portion 42 may have small bubbles as indicated at 47 which assist in breaking up the light rays and increasing the general illumination.

Fixture covers of this type have a radiant glow which make them distinctive in appearance and pleasing to the eye.

As best shown in Fig. 5, the fixture comprises a box 48 having a hinged cover 49 which supports an adjustably positioned bracket 50 which in turn holds the socket 51 for the lamp 52. The bracket carries at its outer end a reflector 53 so that no matter where the lamp unit is positioned within the box, the reflector is directly behind the lamp. The bracket is slidably carried on the cover 49 by a pair of screws 54 which are threaded into the bracket 50 and travel in a slot 55 provided in the box cover.

Since the light fixture shown in Figs. 4-6 inclusive, is closer to the reading plane than the fixture shown in Figs. 1-3 inclusive, vertical adjustment of the lamp with respect to the lens 41 is relatively unimportant although suitable provision may be made at the lower end of the bracket 50 to accommodate vertical adjustment.

As before, a light screen 46 may be used on the inner side wall of the cover 31 for color effect.

The fixtures shown in Figs. 7 and 8 are primarily intended for ceiling installations, the one in Fig. 7 comprising a lens cover 56 which is threaded into a somewhat elongated depending base 57 in order to give the side or light diffusing portion 58 a better opportunity to provide even ceiling illumination, and the fixture shown in Fig. 8 accomplishes somewhat the same result by having the cover 59 of substantially spherical form.

The fixtures shown in Figs. 1-3 inclusive all have the novel aesthetic effect of an illuminated crystal and the effect is more pronounced when at least the side portions of the cover are provided with bubbles.

In Figs. 9-12 inclusive, two further modifications of the lighting fixture are shown, the covers of which are characterized by having re-entrant lens portions 60 surrounded by a depressed annular diffusing portion 61. In Fig. 12, the lens is of the optical type and in Fig. 13, the lens is of the prismatic type. In both forms, however, the lens serves to collect the light rays and concentrate them into a vertical beam to be thrown on the reading plane below.

The marginal diffusing portion 61 may be provided with beading, as indicated at 62 in Fig. 12 to give the cover an ornate appearance and assist in the distribution of the light for general illumination, or it may be plain, as shown in Fig. 13 in which event, the inside annular trough 63 would be frosted or enameled to give this portion of the cover light diffusing characteristics.

In Fig. 12, the fixture itself comprises a reflector 64 having a split neck 65 forming a jaw which is adapted to adjustably clamp the lamp socket 66 in its desired vertical position with respect to the lens 60. The socket carries a standard lamp 67 and ventilation of the fixture is accomplished by convection with air entering

the reflector through openings 68 and leaving the reflector through openings 69.

Attached to the mouth of the rim is a retaining rim 10 provided with screw threads 71 into which the fixture cover is screwed into place and preferably the upper edge of the cover is serrated as indicated at 72 to cooperate with the locking pawl not shown, which is of the same character as the pawl 45 shown in Fig. 2.

Near the base of the reflector 64 is a band or screen 73 which may be color tinted to reflect a certain amount of color into the main beam transmitted through the lens 60, but a greater amount through the light diffusing portion 61 of the cover.

An alternative method of introducing color into the light emitted by the fixture is by employing a color screen 74 (see Fig. 13) of gelatin, or other suitable light filtering material.

The lamp cover shown in Fig. 13 is supported by clips 75 in a retaining ring 76 which is swung from a concealed hinge 77 rigid with the reflector 64. Ventilation openings 68 and 69 are provided as in the fixture shown in Fig. 12.

One advantage of the re-entrant lenses which characterize the fixtures shown in Figs. 12 and 13, is that the surrounding diffusing portions 61 tend to screen the light source from the eyes of persons who are not directly in the vertical beam given out by the fixture. Another advantage is that the total depth of the fixture is held to a minimum and at the same time, the depressed annular diffusing portion 61 provides better general illumination immediately adjacent to the beam.

It should be understood that the treatment of the lamp cover embodying lens and diffusing

portions can be varied to suit conditions, using numerous combinations of frosting, enameling, color tinting and bubbles in the glass, without departing from the spirit of this invention.

5 I claim:

1. In a lighting fixture, a source of white light, a cover below the source through which light rays are transmitted for producing a given light distribution, said cover having light transmitting means for throwing a vertical beam of white unfiltered light and a concentric diffusing portion for casting light laterally, said diffusing portion including annular prisms adapted to bend the light rays upwardly, and a color screen inside the cover placed with respect to the light source and cover so as to direct colored light from the source through the light diffusing portion and to diffuse colored light from the screen into the vertical beam of white light.

2. In a lighting fixture, a source of white light, a cover below the source through which light rays are transmitted for producing a given light distribution, said cover having light transmitting means for throwing a vertical beam of white unfiltered light and a concentric diffusing portion for casting light laterally, a reflector behind the source reflecting white light through the light transmitting means, said diffusing portion including annular prisms adapted to bend the light rays upwardly, and a color screen inside the cover placed with respect to the light source and cover so as to direct colored light from the source through the light diffusing portion and to diffuse colored light from the screen into the vertical beam of white light.

LEMMUEL L. STEWART.
